(57) **CLAIM**

The ornamental design for an orthopaedic brace as shown and described.

DESCRIPTION

FIG. 1 is a front perspective view of an orthopaedic brace according to my new design;

FIG. 2 is a right side view thereof;

FIG. 3 is a rear view thereof;

FIG. 4 is a left side view thereof;

FIG. 5 is an enlarged detail of a front side perspective view thereof;

FIG. 6 is an enlarged, partial detail front view thereof; and, FIG. 7 is an enlarged detail of the rear view, in an alternate state of use showing the support strap in an open position. The evenly spaced broken lines around the torso show environmental structure and form no part of the claimed design.

The dash-dot-dash broken lines form the boundary of enlarged views and form no part of the claimed design.
